UNITED STATES PATENT OFFICE.

ANDREW G. PAUL, OF BOSTON, MASSACHUSETTS.

LOOP FOR TRANSFERRING LIQUIDS.

1,097,594.

Specification of Letters Patent. Patented May 19, 1914.

Application filed August 10, 1912. Serial No. 714,326.

To all whom it may concern:

Be it known that I, ANDREW G. PAUL, a citizen of the United States, and a resident of Boston, in the county of Suffolk and 5 State of Massachusetts, have invented a new and useful Improvement in Loops for Transferring Liquids, of which the following is a specification.

My invention relates to a loop for transferring liquids from a low point into a vessel, such as a boiler, in which a pressure is maintained above atmosphere, and it is particularly adapted for transferring the water of condensation in a steam heating 10 system, or steam apparatus, from a point at or below the level of the water in the boiler back to the boiler against whatever pressure may exist therein.

The object of the invention is to provide 20 an apparatus by means of which the water of condensation, or other liquid, which accumulates at the tail end of the system, or at other places therein, may be transferred automatically and continuously and without 25 the use of a pump and other expensive apparatus, back to the boiler or the source of supply, against whatever pressure may exist therein, and to do this either when the apparatus is first put into operation, or 30 at any time at which such water of condensation or other liquid may accumulate at the points referred to.

Another object of the invention is to cause 35 the water of condensation, or other liquid, to be returned in this manner while it is comparatively hot, so as to save the heat units contained therein, and thereby to increase the economy of the apparatus.

Another object of the invention is to cause 40 the return of the water of condensation, or other liquid, to be continuous and at such a rate that the flooding and consequent choking of the apparatus may be prevented.

My invention consists first in providing 45 a loop having a supply leg, a discharge leg, and a connecting pipe at or near the top of these legs, and in combining with these elements one or more cross-over pipes connecting the legs at one or more lower points.

50 My invention also consists in providing these crossover pipes with check valves to prevent any back flow from the discharge leg to the supply leg.

My invention also consists in providing 55 an automatic escape valve near the top of the loop to reduce the pressure at that point,

or to maintain a relatively low pressure there.

My invention also consists in making the discharge leg of larger cross-sectional area 60 than the supply leg, or in providing the discharge leg at proper points with a reservoir of large cross-sectional area into which the discharge leg opens and discharges, the reservoir being connected with the boiler.

65 My invention also consists in combining such a loop with a steam boiler in such a manner that whatever pressure may be maintained in the boiler, the water of condensation will be automatically discharged into the boiler 70 from time to time against said pressure.

75 My invention also consists of other features of construction and combinations of parts, all as hereinafter described and claimed.

The invention is fully illustrated in the accompanying drawings in which—

Figure 1 is a side elevation of one form or modification of my improved device, and Fig. 2 is a side elevation of another form 80 or application of my improved device shown in connection with a boiler and with a steam heating system.

Referring to Fig. 1, 1 is a tank to receive the water of condensation or other liquid 85 which is to be returned to the boiler or other vessel. 2 is a pipe leading into the tank 1 through which the water of condensation flows to the tank. 3 is the supply leg of the loop which extends down into the tank 1 90 to a point below the bottom of the pipe 2. 4 is the discharge leg of the loop which is represented as having a vertical portion and a horizontal portion. Both the supply leg and the discharge leg are represented as being broken away at intermediate parts to indicate that they may be made of any desired length or height. The two legs of the loop are connected by a connecting pipe 5 which is at or near the top of the legs. 6 is a cross- 95 over pipe which connects the supply leg and the discharge leg at a lower point. Any number of cross-over pipes may be used. In the particular form shown in Fig. 1 only one cross-over pipe is employed. In the 100 particular form of the invention shown in Fig. 2 two cross-over pipes are shown as will be explained later. In the form shown in Fig. 1 the cross-over pipe 6 is placed at such a point that the pressure which is main- 105 tained in the boiler will be sufficient to raise the water of condensation in a solid column

75

90

95

100

105

110

from the tank 1 up to the pipe 6 if sufficient water should accumulate in the tank 1 and the pipe 2 to form such a solid column of water. If more than one cross-over pipe is used, the lowest cross-over pipe should be placed at such a point as to secure this result. 7 is a check valve placed in the cross-over pipe 6 designed to prevent any back-flow from the discharge leg to the supply leg. 8 is a receiver in the discharge leg, or with which the discharge leg is connected and into which the discharge leg opens. This receiver is made with a large cross-sectional area as indicated in the drawing. 9 is a pipe leading from the lower end of the receiver to the boiler which is not shown in this figure. This pipe is connected with the boiler below the water level thereof. 10 is a check valve placed in the horizontal portion of the pipe 9 to prevent any back-flow from the boiler into the receiver or the discharge leg. 11 is a water gage connected in any ordinary way with the receiver 8 to indicate what the water level is in said receiver. 12 is an escape pipe leading from the upper end of the loop and provided with an automatic escape valve or automatic valve 13. This valve 13 may be an ordinary automatic valve which will permit the escape of water and air while preventing the escape of steam, or it may be a safety valve which will open at a given or predetermined pressure and let anything out so as to prevent the increase of any pressure above the desired point at the upper end of the loop. The pipe 12 preferably leads down to the basement or to some suitable point where the escaping fluids can be conveniently discharged. 14 is an escape pipe similar to the pipe 12, leading from the upper end of the receiver 8 and provided with an automatic escape valve, or an automatic air valve 15 similar to the valve 13.

The operation of this apparatus is as follows: We will assume that it is being used in a steam heating system, in which case the pipe 2 is the return pipe for the water of condensation leading from the tail end of the system, or from any other point from which the system may be drained. When the system is started or put into operation, the tank 1 and the pipe 2 are likely to be full of cold water, or a sufficient quantity of practically cold water is likely to flow to the tank 1 to fill it and the adjoining pipes. In order to discharge this water it must be raised by boiler pressure up to the level of the cross-pipe 6. If the pressure which is carried in the boiler is say five pounds, the cross-over pipe 6 should be placed at a point less than ten feet above the tank 1. The pressure in the pipe leading to the tank 1 will be substantially the same as that in the boiler, to wit, substantially equal to five pounds. This pressure will force the water

from the tank 1 in a solid column up to the crossover pipe 6 and through that pipe into the discharge leg 4 and into the receiver 8. At this time, that is, at the beginning of the operation of the system, the pressure in the receiver 8 will be atmospheric so that there will be no pressure in that receiver to oppose the lifting of the water. As soon as the water has been discharged from the tank 1, or the column of solid water in the supply leg 3 has been broken, the steam or air or gas from the heating system will flow up through the pipe 3 and, by reason of its velocity, will carry along with it globules or particles of water from the tank 1 up to the top of the loop or through the cross-pipe 6 and over into the discharge leg 4, and hence into the receiver 8. At the same time the pressure of five pounds will extend into the discharge leg of the loop and will be exerted on top of the water in the receiver. When the water in the receiver or in the discharge leg, has risen to a sufficient height to overcome the resistance of the pipe 9 and the check valve 10 and the pressure in the boiler, the water will be discharged from the receiver 8 into the boiler, and this discharge will continue until the water in the receiver 8 has fallen to such a level that the water column is no longer great enough to overcome frictional resistance of the pipe 9 and the check valve 10, together with the boiler pressure and the check valve will then close, and will remain closed until the water in the receiver has again risen high enough to open the check valve, when the operation will be repeated.

It is an important feature of the invention to have the receiver 8 of horizontal cross-sectional area considerably larger than that of the supply leg. This helps to prevent the flooding of the loop by a sudden outflow of water from the system. It happens every now and then in every heating system that there is an unusual rush of water of condensation into the tank 1 and into the loop. If the receiver 8 were not used the discharge leg would be certain at such times to be entirely filled to the top of the loop and the supply leg would likewise be filled, or the supply leg and discharge leg would be filled up to the point to which the pressure in the system would raise the water. If the loop becomes full for any cause its operation ceases because the flow of steam or air or gas is cut off, and consequently no water can be carried up by an outflowing current, and the loop is put out of action. The only way in which the loop could then be cleared would be by blowing the water out into the atmosphere. This would require a manipulation of the system that would be very inconvenient and troublesome as well as expensive or wasteful. The system would not clear itself of water automatically. By using the

receiver 8 as described with large cross-sectional area, a reservoir of sufficient size is provided to receive whatever rush of water may come over at any time and to prevent the loop from becoming full or choked with water. Consequently pressure from the system extends through the loop at all times and the operation of the loop is continuous. No water is discharged into the boiler until the water in the reservoir 8 rises to the proper level, but as soon as this happens the check valve in pipe 9 is opened and the water is discharged into the boiler and continues to discharge until the water in the reservoir has fallen to the minimum level. During all this time the check valve is fully open. When the check valve does open it therefore remains open for a much longer time than would be the case if the receiver 8 were not used. If the discharge leg had no receiver on it the water would rise in the discharge leg until there was a sufficient water column to open the check valve, then water would be discharged into the boiler until the water in the discharge leg fell to the minimum level. But this would happen very quickly and but a small quantity of water would be discharged into the boiler in the interval. The check valve 10 would remain open but a short time. It would be opening and closing not only intermittently but frequently, and this constant opening and closing would reduce the actual volume of flow through it very materially. When the receiver is used, as soon as the water has risen in it to the maximum level the check valve 10 is opened wide, and there is a continuous flow through it until the water has fallen in the receiver to the minimum level. This flow is enough to take care of and discharge any possible volume of water that can be carried over by the loop, so that the check valve and its pipe 9, when used with the receiver, has a capacity sufficient at any time to handle any amount of water that is brought over by the action of the loop. It is essential to this operation that the receiver 8 should be placed at the proper elevation, to wit, at such a point that the level to which the water must rise in the discharge leg in order to cause a discharge into the boiler, shall be below the top of the receiver, and that the level to which the water must fall in order to cause the check valve 10 to be closed must be above the bottom of the receiver. In other words, the maximum level of the water that is necessary to open the check valve, and the minimum level of the water at which the check valve closes, must both be within the receiver itself or at some point between the top and bottom of the receiver.

In Fig. 1, 16 represents the level at which the water column will open the check valve and begin to discharge into the boiler, and

17 represents the level at which the check valve will be closed and the discharge stopped. Some advantage would be secured by placing the receiver above the level 16 as it would still act as a reservoir to prevent, ⁷⁰ or help to prevent, the flooding of the loop, but to secure the full advantage of the receiver it must be placed in the position previously described.

If at any time while the system is in operation water accumulates in the tank 1 so rapidly that that tank becomes full of water so as to suspend the action of the loop, the pressure at the top of the loop will rapidly fall by reason of the condensation of the steam and by reason of the fact that the automatic air valve 13 will open when the flow through the loop ceases. The pressure at the upper part of the loop will thereby be rapidly reduced to atmospheric pressure. ⁸⁰ In this way a differential pressure will be established between the pipe 2 or tank 1, and the upper end of the loop, which will cause the water to be lifted out of the tank 1 in a solid column up to the cross-over pipe ⁹⁰ 6, and will cause it to flow through that crossover pipe into the discharge leg 4 until the solid water column in the pipe 3 will be against broken when the operation of the loop will be re-established. Thus whenever ⁹⁵ sufficient water collects in the tank 1 during the operation of the system to fill it full of solid water, the loop will clear itself automatically and will again begin to operate in the manner explained above. The system ¹⁰⁰ is thus kept in continuous and automatic operation, and the water is continuously discharged from the tank 1 over the top of the loop or through the cross-pipe 6 at very ¹⁰⁵ high temperatures and with great resulting economy.

In all loops previously known to me the cold water that collected in the loop at the beginning had to be blown out into the atmosphere by boiler pressure, and the boiler ¹¹⁰ pressure had to be raised to a sufficient point to produce this result, and the same was true whenever the loop became clogged with water for any reason during the regular operation of the system. In the present invention this is not true. As already explained, the solid water is discharged into the boiler automatically both when the system is first put into operation and at any time during the operation of the system ¹¹⁵ 120 when such solid body of water accumulates therein.

In Fig. 2 my invention is shown as embodied in a steam heating system. 18 is the boiler. 19 represents the level of the water ¹²⁵ in the boiler. 20 is the supply main leading from the dome of the boiler to the heating system. 21 is the supply pipe leading to the radiators 22, 22. Only two radiators are shown, but as many radiators may be used ¹³⁰

as desired. 23, 23 are ordinary hand supply valves in the supply branches leading to each radiator. 24, 24 are return valves of any suitable construction. 25 is the return main through which the water of condensation flows from the system. 26, 26 are check valves placed in short branches of the return pipe leading from the separate radiators to the return pipe 25. 27 is a drip pipe leading from the base of the supply pipe 21 to the horizontal pipe 28 which is connected with the boiler below the water level and through which the water of condensation received from the various parts of the system is returned to the boiler. 29 is a check valve in the pipe 27. 30 represents a drip pipe leading from some other part of the heating system and connecting with the pipe 27. 31 is a vertical pipe of relatively large diameter which acts as a tank or reservoir to receive the water of condensation from the return pipe 25. The pipe 31 empties into the pipe 28. 32 is a check valve placed in the pipe 28 to prevent any back flow from the boiler into the pipe 31. 33 is the supply leg of the loop. 34 is the discharge leg of the loop. In this form of the invention the entire discharge leg is made larger in diameter than the supply leg, being represented in the apparatus shown in Fig. 2 as having a diameter of about three times that of the supply leg. 35 is a pipe connecting the two legs of the loop at or near their upper ends. 36, 36 are cross-over pipes connecting the supply leg with the discharge leg at different points or levels as shown. In the particular construction illustrated in Fig. 2, two of these crossover pipes are used, but it will be apparent that a larger number may be employed if necessary. These crossover pipes are provided with check valves 37, 37 to prevent back flow into the supply leg. The discharge leg is connected at its lower end with the pipe 28. It is also provided near its lower end with check valve 38. The supply leg 33 projects down into the reservoir 31 to a point on a level with or below the bottom of the horizontal portion of the pipe 25. 39 is an escape pipe connected with the upper end of the loop to permit the escape of air and gas. It is provided at its upper end with the automatic escape valve or automatic air valve 40 which may be of any desired construction. I prefer to use a valve which will permit the escape of air and gas but prevent the escape of steam. The escape pipe 39 is provided at its lower end with a check valve 43. 41 represents a return pipe coming from some other part of the system and emptying into the pipe 25. 42 is an ordinary hand valve or gate valve in the pipe 28, by means of which that pipe may be closed.

The operation of this form of my invention is substantially the same as that of the

form shown in Fig. 1 except that the operation is materially improved by the use of a plurality of crossover pipes, and also by connecting the tank or reservoir 31 directly with the boiler. The water flowing from the heating system through the pipes 25 and 41, first accumulates in the pipe 31, and if the water column in that pipe is of sufficient height to overcome the boiler pressure, or the difference between the boiler pressure and the pressure in the pipes 25 and 41, the water will flow directly into the boiler without passing over the loop. But if this differential becomes greater the water will be carried over the loop in the manner already explained in connection with Fig. 1. There is a marked advantage in having several crossover pipes. When the water accumulates in the reservoir 31 at the beginning of the operation or during the operation, the pressure which is back of it in the heating system will force it up through the supply leg 33 to the first crossover pipe and possibly higher than that. The water will be forced up very quickly, and it may not escape through the first crossover pipe as rapidly as it rises up in the supply leg. The second crosspipe which is placed, say twenty seven inches above the first, will operate as an additional channel of escape for this solid water from the supply leg to the discharge leg. It is important to have the solid water discharged from the supply leg to the discharge leg as rapidly as possible so as to establish and bring into action the current of steam or air or gas in the supply leg which serves to carry the water up over the top of the loop. The additional crosspipes aid in accomplishing this result. If the pressure in the reservoir 31 is sufficient to lift the water as high as the second or third crosspipe, the flow from the supply leg to the discharge leg will be all the more rapid, and the supply leg will be freed from the solid column of water in shorter time. Water tends to flow in straight lines, and if there is sufficient pressure in the reservoir 31 to lift the water up to the second crosspipe, the chances are that the water will rise, at least for a time, in the supply leg as high as the second crosspipe, and an appreciable amount of time would be consumed in its discharge through the lowest crosspipe if that were the only one. But this discharge is made much more rapid by the use of a number of cross-over pipes. If the supply leg 33 becomes filled with a solid column of water for some distance above its lower end, the steam in the upper part of the loop will be condensed, thereby reducing the pressure. The water in the leg 33 will therefore be lifted to a point corresponding to the difference between the pressure in the pipe 25, and the pressure in the top of the loop. This will raise the water in the leg 33 high

- enough to make it flow through one or more of the crossover pipes 36 into the discharge leg until the solid column of water in the supply leg 33 will be broken and the normal 5 operation of the loop will be again established. When the column of water in the supply leg has been broken, the pressure at the top of the loop will become practically the same as the pressure in the return pipe 10 25, which is nearly the same as the pressure in the boiler. This pressure will operate on top of the water column in the discharge leg to aid in discharging the water into the boiler.
- 15 The discharge leg of the loop must extend upwardly for a sufficient distance to provide for a water column that will be high enough, under any circumstances, to overcome any boiler pressure that may be used in the system.
- 20 Important advantages are secured by my invention. Whenever water accumulates, or tends to accumulate, at the tail end of the system, it is at once carried over into the discharge leg of the loop until a sufficient 25 column of water is produced therein to cause the water to be fed into the boiler. This is done automatically and by a very simple and inexpensive apparatus. The water is discharged into the boiler as soon as it accumulates in any substantial quantity, and it is therefore fed into the boiler while it is still hot, thereby economizing in the use of heat. The flooding of the apparatus is prevented. It is never necessary to blow the 30 water out into the atmosphere either when the system is first put into operation or at any time when, for one reason or another, there has been an unusually large flow of 35 water to the loop.
- 40 What I claim as new and desire to secure by Letters Patent, is:
1. In a loop for transferring liquids, the combination of a supply leg, a discharge leg, 45 a connecting pipe at or near the top of the legs, and a cross-over pipe connecting the legs at a lower point.
  2. In a loop for transferring liquids, the combination of a supply leg, a discharge leg, 50 a connecting pipe at or near the top of the legs, and a cross-pipe connecting the legs at a lower point, and a check valve in the cross-over pipe.
  3. In a loop for transferring liquids, the 55 combination of a supply leg, a discharge leg, a connecting pipe at or near the top of the legs, and a plurality of cross-over pipes connecting the legs at different levels.
  4. In a loop for transferring liquids, the 60 combination of a supply leg, a discharge leg, a connecting pipe at or near the top of the legs, a plurality of cross-over pipes connecting the legs at different levels, and check valves in the cross-over pipe.
  - 65 5. In a loop for transferring liquids, the combination of a supply leg, a discharge leg, a connecting pipe at or near the top of the legs, an automatic escape valve near the top of the loop to reduce the pressure at that point, and a cross-over pipe connecting the legs at a lower point.
  6. In a loop for transferring liquids, the combination of a supply leg, a discharge leg, a connecting pipe at or near the top of the legs, an automatic air valve near the top of 75 the loop, and a cross-over pipe connecting the legs at a lower point.
  7. The combination with a boiler of a loop for feeding condensed liquid to the boiler, consisting of a supply leg, a discharge leg, 80 connected with the boiler, a connecting pipe at or near the top of the legs, and a cross-over pipe connecting the legs at a lower point.
  8. The combination with a boiler of a 85 loop for feeding condensed liquid to the boiler, consisting of a supply leg, a discharge leg connected with the boiler, a connecting pipe at or near the top of the legs, and a cross-over pipe connecting the legs at 90 a lower point, and a check valve in the cross-over pipe.
  9. The combination with a boiler of a loop for feeding condensed liquid to the boiler, consisting of a supply leg, a discharge leg connected with the boiler, a connecting pipe at or near the top of the legs, 95 and a plurality of cross-over pipes connecting the legs at different levels.
  10. The combination with a boiler of a 100 loop for feeding condensed liquid to the boiler, consisting of a supply leg, a discharge leg connected with the boiler, a connecting pipe at or near the top of the legs, a plurality of cross-over pipes connecting the 105 legs at different levels, and check valves in the cross-over pipes.
  11. The combination with a boiler of a loop for feeding condensed liquid to the boiler, consisting of a supply leg, a discharge leg connected with the boiler, a connecting pipe at or near the top of the legs, 110 a cross-over pipe connecting the legs at a lower point, a check valve in the cross-over pipe, and an automatic valve near the top 115 of the loop.
  12. The combination with a boiler of a loop for feeding condensed liquid to the boiler, consisting of a supply leg, a discharge leg connected with the boiler of 120 larger cross-sectional area than the supply leg, a connecting pipe at or near the top of the legs, and a cross-over pipe connecting the legs at a lower point, and a check valve in the cross-over pipe.
  13. The combination with a steam boiler of a loop for feeding water of condensation to the boiler, consisting of a supply leg, a discharge leg connected with the receiver, a connecting pipe at or near the top of the 130

legs, a cross-over pipe connecting the legs at a lower level, a check valve in the cross-over pipe, and a receiver of large cross-sectional area into which the discharge leg 5 opens, the receiver being connected with the boiler.

14. The combination with a steam boiler of a loop for feeding water of condensation to the boiler, consisting of a supply leg, a 10 discharge leg connected with the receiver, a connecting pipe at or near the top of the legs, a cross-over pipe connecting the legs at a lower level, a check valve in the cross-over pipe, and a receiver of large cross-sec-

tional area into which the discharge leg 15 opens, the receiver being connected with the boiler and being so arranged as to extend from the level at which the water begins to feed into the boiler to the level at which the feeding stops. 20

In testimony whereof, I have signed my name to this specification, in the presence of two subscribing witnesses.

ANDREW G. PAUL.
